P. LORANG

MAGNETIC SEPARATOR

Filed March 28, 1923

Fig. 1.

Fig. 2.

Inventor:

Paul Lorang

UNITED STATES PATENT OFFICE.

PAUL LORANG, OF METZ, FRANCE.

MAGNETIC SEPARATOR.

Application filed March 28, 1923. Serial No. 628,329.

To all whom it may concern:

Be it known that I, PAUL LORANG, solicitor, a citizen of the French Republic, residing at Metz, France, have invented 5 certain new and useful Improvements in Magnetic Separators, of which the following is a specification.

The present invention relates to magnetic separators, and consists in the combinations 10 and arrangements of elements hereinafter disclosed and set forth in the accompanying claims.

The invention has for its purpose to provide a magnetic separator which will be 15 positive and accurate in operation, and adapted for the separation of the particles of iron from the dust of furnace-smoke or the metallic fume of furnaces.

According to the invention the dust or 20 fume is conveyed along an iron-plate, which is magnetized by means of electro-magnetic coils. Owing to the long way of the dust along the said plate, a careful separation 25 of the particles of iron from the dust is secured. The gathering of the particles of iron from the plate can be simply accomplished by interrupting the electric current of the electro-magneto coils.

With the above objects, and other incidental objects, in view, the invention consists 30 of the devices and parts, or their equivalents, as hereinafter set forth.

In further describing the invention, reference will be made to the accompanying 35 drawing in which—

Fig. 1 is a side elevation, partly in section;

Fig. 2 is a plan view of the device;

Fig. 3 is a cross-section taken on the line 40 3—3 of Fig. 1;

Fig. 4 is a top view of a modified form of the iron-plate or lid; and

Fig. 5 shows a fragmentary view of a 45 conveyer with shovels according to the invention.

Referring to the drawing, the letter *a* denotes a reservoir for taking up the dust from the waste gases of furnaces, or the refuse of converters in steel-works. The 50 reservoir has two openings *b* for the connection with the two tubes or channels *c*. In each of these tubes a helical conveyer *d* is arranged. The tubes are provided with large slots in the upper part, which slots 55 are covered by convexed iron-plates or lids

e. The latter are capable of being turned about the axles *g* and can be magnetized by means of electro-magnetic coils *h*, which are arranged in or on the plates *e*. The coils *h* may be supplied with electric current 60 in the well known matter. Alongside of the tubes or channels *c* are arranged trays or channels *i* with helical conveyer or screws *f*, for gathering and transporting the iron-particles to a carriage *k*. The conveyers or 65 screws *d* and *f* are turned by belts *l* or other means.

It is useful, to provide scoop or shovels *m* between the windings of the helical conveyers *d*. By means of the shovels *m* the 70 dust is raised and led past near the plates or lids *e*, see Fig. 3.

As shown in Fig. 4 the lids of the channels *c*, may consist of two parts *e*₁ and *e*₂, 75 which fit into each other by means of cuts. The parts *e*₁ and *e*₂ are to be moved alternately at opposite directions about the axles *g*₁ and *g*₂.

The working of the described device is 80 the following:—The ferriferous dust from the waste gases of furnaces is transported from the reservoir *a* by means of the conveyers *d*. The plates *e* with the electric coils *h* are working as electro-magnets and 85 separate the particles of iron from the dust by attracting the said particles. In periods,

the plates or lids are turned outwardly into the position indicated in Fig. 3 with dotted lines. In this position the electric current of the coils *h* will be interrupted and therefore the particles of iron sticking to the plates *e* drop into the channels *i* and are transported to the carriage *k* by the conveyers *f*. The dust delivered from the 90 particles of iron will be conveyed into the 95 carriages *n* by the screws *d*. By the described device it is possible to separate completely the iron particles from the flue dust discharged from blast furnaces. Therefore, the treating of the latter in furnaces 100 is not required. Further, with this device, the ooze of gas-refiners may be delivered from iron.

It must be understood that my invention is not to be limited to the specific form of the construction and arrangement as shown and described here, but that variations may be made in practice without however departing from the spirit and principles of 105 the invention.

Having thus described my invention, what I claim as new, and desire to secure by Letters Patent is:—

1. In a magnetic separator, the combination of an iron plate with electro-magnetic coils, a helical conveyer for transporting the pulverized material along the iron plate, a channel for the conveyer, and shovels arranged between the windings of the helical conveyer, substantially as and for the purpose described.

2. In a magnetic separator, the combination of an iron plate with electro-magnetic coils, a helical conveyer for transporting the pulverized material along the iron plate, shovels arranged between the windings of the helical conveyer, and a divided cylindrical case for the latter, whereby the upper

part of said case is the iron plate and carries the said electro-magnetic coils, substantially as and for the purpose described.

3. In a magnetic separator, the combination of a helical conveyer for transporting the pulverized material, a divided cylindrical case for said conveyer with a lid carrying electro-magnetic coils, shovels arranged between the windings of the conveyer, means for enabling the said lid of being turned aside and a second helical conveyer arranged in a channel for collecting and transporting the separated iron particles, substantially as described.

In testimony whereof I affix my signature.

PAUL LORANG.
